[57] CLAIM

The ornamental design for an off-shore fish feeder, as shown and described.

DESCRIPTION

FIG. 1 is an upper rear perspective view of an off-shore fish feeder showing my new design, both sides are identical to the rear;

FIG. 2 is a lower rear perspective view thereof;

FIG. 3 is a front elevational view thereof;

FIG. 4 is a top plan view thereof;

FIG. 5 is a bottom plan view thereof; and,

FIG. 6 is a rear elevational view thereof, the broken lines are for illustration only and form no part of the claimed design.
